UNITED STATES PATENT OFFICE.

JOHN L. ORNESS, OF LA MOURE, NORTH DAKOTA.

SELF-CLOSING DOOR.

1,172,038.

Specification of Letters Patent. Patented Feb. 15, 1916.

Application filed April 17, 1915. Serial No. 22,148.

To all whom it may concern:

Be it known that I, JOHN L. ORNESS, a citizen of the United States, residing at La Moure, in the county of Lamoure and State of North Dakota, have invented certain new and useful Improvements in Self-Closing Doors; and I do declare the following to be a full, clear, and exact description of the invention, such as will enable others skilled in the art to which it appertains to make and use the same.

This invention relates to self-closing doors and more particularly to the means for opening them.

15 The primary object of the invention is to provide a door of this character especially constructed for use on hog houses to permit the swine to open the door and pass in and out as desired and the door to close automatically after they enter or leave the building.

25 Another object of the invention is to provide a door of this character which is simple and efficient in construction, which has no parts to get out of order, and which will move into closed position immediately after the passage of the animal therethrough and may be readily opened by the animal from either side.

30 With these and other objects in view, the invention consists of certain novel features of construction, and the combination and arrangement of parts as will be more fully described and claimed.

35 In the accompanying drawings: Figure 1 represents a front elevation of a portion of the front wall of a house equipped with this improved door showing it in closed position; Fig. 2 is a horizontal section thereof taken on the line 2—2 of Fig. 1; Fig. 3 is a detail perspective view of the door taken from the inside. Fig. 4 is a horizontal section of the door taken on line 4—4 of Fig. 1.

40 While it is to be understood that this improvement may be applied to any self closing door it is shown in the embodiment illustrated applied to a door 2 hinged at its upper edge to the upper end wall of a door opening 1 and of a size to shut within said door opening so that the inner and outer faces of the door and the side wall of the building will be arranged flush with each other when the door is in closed position, but not necessarily so. This door 2 is pro-

vided on its opposite side edges of the inner 55 face thereof with beveled or cutaway portions 3 preferably disposed near the lower end and which are designed to facilitate the outward opening of the door from the inside by the hogs which may push against 60 the door on the inner face thereof and thus cause it to swing outwardly, the tendency of the hogs being to push against the recessed portion of the door into which their snouts may readily be inserted.

65 Secured to the outer face of the door 2 along the opposite side edges thereof are lateral projections here shown in the form of outwardly inclined wings 4 and 5 which project beyond the side edges of the door 70 and overlap the adjacent edges in the opening 1 and in addition to forming door opening elements for engagement by the animals serve as stops for limiting the inward or closing movement of the door. These wings 75 4 and 5 are also recessed on their inner faces as shown at 6 to facilitate the passage between them and the side wall of the building of the snouts of the hogs so that they may readily force open the door when they 80 desire to enter from the outside, it being necessary that sufficient space be provided between these wings and the side wall of the building for the insertion of the snouts or feet of the animals to enable them to 85 readily open the door. These wings 4 and 5 as shown terminate at their upper ends below the hinged connection of the door with the building and in the form shown are designed also to serve as weights for the 90 door to cause it to drop downwardly into closed position immediately the animal passes from under it.

95 From the above description, it will be obvious that this door is composed of three parts; to wit, the door proper and the two wings, which latter while shown attached may be made integral therewith if desired, and the door may be constructed of any suitable or desired material, either wood or 100 metal, and hence there are no parts which could possibly get out of order, and the door as shown will swing automatically into closed position by the force of gravity immediately the obstruction passing under it 105 is removed, and thus will be tightly closed at all times except during the inward or outward passage of an animal through the

door, the gist of the invention residing in the means provided to enable the animals to open the door.

I claim as my invention:

- 5 1. The combination of a wall having a door opening therein, a self-closing door for said opening, and elements carried by said door at opposite sides thereof and inclined laterally to overlap the side edges of the 10 door opening.
2. The combination of a wall having a door opening therein, a self-closing door for said opening and a laterally inclined wing carried by one edge of said door forming an 15 opening element for actuation by the nose or foot of an animal.
3. The combination of a wall having a door opening therein, a self-closing door for said opening, and outwardly inclined wings at opposite edges of said door form- 20

ing opening elements therefor, said wings having their inner faces recessed to facilitate the engagement of the nose of an animal therewith from one side.

4. The combination of a wall having a 25 door opening therein, a self-closing door for said opening, outwardly inclined wings at the opposite side edges of said door forming opening elements therefor, said wings and door having their inner faces at the side 30 edges thereof recessed to facilitate the opening of the door by an animal from either side of the wall.

In testimony whereof I have hereunto set my hand in presence of two subscribing 35 witnesses.

JOHN L. ORNESS.
